UNITED STATES PATENT OFFICE.

EDWARD ERICKSON, OF BOSTON, MASSACHUSETTS, ASSIGNOR TO THE BOYLSTON MANUFACTURING COMPANY, OF BOSTON, MASSACHUSETTS, A CORPORATION OF NEW JERSEY.

HEEL-BREASTING MACHINE.

1,067,216.

Specification of Letters Patent.

Patented July 8, 1913.

Application filed July 5, 1907, Serial No. 382,171. Renewed November 12, 1912. Serial No. 731,037.

To all whom it may concern:

Be it known that I, EDWARD ERICKSON, of Boston, in the county of Suffolk and State of Massachusetts, have invented certain new and useful Improvements in Heel-Breasting Machines, of which the following is a specification.

This invention relates to heel breeding machines and has for its object to provide a machine which shall trim the breast of a heel on a shoe supported thereon in such a way that the trimming knife shall in every case, cut precisely to and yet not into the shank of the shoe, regardless of whatever variation may exist in the thickness of the heels of different shoes thus trimmed.

In a machine of this kind, the depth of the cut should always be such as to extend to the shank of the shoe so as to insure a cleanly cut surface on all parts of the breast of the heel, and yet the cut should not be so deep as to enter into the shank of the shoe. By cutting into the shank of a shoe, as some machines do, especially when the shoe is provided with a heel somewhat thinner than that for which the machine is adjusted, not only is the appearance of the shoe impaired but the shank is correspondingly weakened at that point. The present invention provides a machine which may be operated upon shoes having heels of varying thicknesses and having shanks of varying thicknesses, in such a way as to avoid all possibility of cutting into the shank itself and yet so as to insure a clean cut to the full depth of the heel. To this end the machine is provided with a fixed stop which is interposed between the work-support or jack and the cutting knife, and which is adapted to be engaged by the shank of the shoe when the jack and shoe are raised to operative position and so to determine the operative position of the shoe by arresting its movement toward the knife. By thus arranging the fixed stop with relation to the work-support and the cutting knife, the point of the shoe to which the knife is intended to cut is in every case positioned coincidentally with the extent to which the knife is capable of cutting.

In connection with the work-supporting mechanism, the machine is provided with an improved clutch-controlling mechanism which is adapted to cause a single cutting stroke of the knife each time a treadle is de-

pressed to raise the work into operative position.

Referring now to the accompanying drawings forming a part of this specification— Figure 1 is a front elevation of a heel breeding machine constructed in accordance with this invention. Fig. 2 is a side elevation with certain parts shown in vertical section. Fig. 3 is a section on the line 3—3 of Fig. 2. Fig. 4 is a section on the line 4—4 of Fig. 1. Fig. 5 is a detail elevation of the clutch members in disengaged position. Fig. 6 is an elevation of a portion of the mechanism which raises the work-support. Fig. 7 is a vertical section of the cutting knife in connection with a shoe supported on the jack. Fig. 8 is a detail view of a portion of the clutch-controlling mechanism shown by Fig. 3 in a different position.

The same reference characters indicate the same parts wherever they occur.

The frame 10 of the machine is provided as usual with a work-support or movable jack 11, a movable cutting knife 12, and the various mechanisms hereinafter described for operating one in connection with the other. The jack 11 is below the knife and movable toward and from it in alignment therewith. The jack 11 is supported by an upright shaft 13, to which it is pivoted by a stud 14. The shaft 13 is held in stationary bearings 15 15 in a portion of the frame and is adapted to be vertically reciprocated to raise or lower the jack. The reason for providing the pivotal connection of the jack at 14 is to permit the jack to be tilted out of alignment with the shaft 13 so as to enable the operator to more readily insert or remove the work. The means for raising the jack comprises a pair of cam members 16 and 17 mounted on the shaft 13, and of which the former is pinned or otherwise secured to the shaft 13 and the latter adapted to rotate relatively thereto. The shaft 13 is prevented from turning in its bearings by a cross-head 18 affixed to the lower end thereof and adapted to slide up and down between guides 19 formed on the frame. The cam members 16 and 17 have faces 20 and 21 which permit the said members to set into each other, as shown in Figs. 1 and 2, and which are adapted to co-operate when the member 17 is rotated so as to raise the member 16. For the purpose of rotating the cam 17, it is provided with

a pinion 22 which rests upon the lower bearing 15 of the frame. The said pinion intermeshes with a rack 23 which is adapted to be reciprocated in stationary bearings 24 24 5 by means hereinafter described. Referring now more to the cam members 16 and 17, it will be observed that they have square end faces 25 and 26 respectively, which engage with each other when the member 16 10 has been raised to its full height. These squared end faces permit subsequent rotation of the cam 17 after the cam 16 has been raised, and by so doing, they transfer the entire weight and pressure of the work-support 15 port to the frame of the machine, thus relieving the pinion and rack 22 23 of the retro-active effect of the work-support, (see Fig. 6).

The rack 23 is connected by a link 27 to 20 the free end of an arm 28 rigidly secured upon a rock shaft 29. The rock shaft is mounted in stationary bearings 30 30 on the base of the frame 10 and is provided with a treadle 31 by which it may be manually 25 oscillated. The rock shaft 29 is further provided with a rigidly secured arm 32 which is connected by a spring 33 to a suitable fixture. The spring 33 normally holds the rock shaft 29 and the jack raising mechanism 30 connected to it, in the positions shown by Figs. 1, 2, and 4 in which the jack is in its retracted position.

The jack 11 is provided with a fixed head 34 to which is pivoted a tilting block 35 35 upon which a shoe may rest when placed upon the jack. The free end of the tilting block 35 is adjustably supported at any desired inclination by means of a stud 36 screw-threaded into the head 34. By this 40 means the inclination of a shoe α , (see Fig. 7), may be determined with relation to the cutting knife 12 so as to cause the latter to give to the breast of the heel either a square or an undercut face as hereinafter described.

45 When a shoe is mounted upon the jack, as shown in Fig. 7, and is raised into operative position by the means hereinbefore described, its shank is adapted to abut against a fixed stop 37 attached to and projecting 50 forwardly from the frame 10. The stop 37 is adapted to arrest the upward movement of the shoe at such a point that the outer surface of the shank b of any thickness whatsoever, shall stop at a predetermined 55 level. When the shoe is brought to this position, the heel c engages a flat plate 38 pivotally mounted at the lower end of a rod 39 which is mounted in a fixed bearing 40, and depressed by a spring 41 which permits the 60 rod to yield upwardly. The rod is provided with lock nuts 42 and a longitudinal slot 43 adapted to receive the end of a stud 44. The stud is screw-threaded in the bearing 40. The stud prevents turning of the rod 39 but 65 permits it to slide longitudinally. By this

means, the shoe is securely held in its operative position upon the jack.

The knife 12 is mounted in a head 45 and clamped therein by means of a block 46 and screw bolts 47 and adjusted with relation to the clamping means by set screws 48. The head 45 is provided with a pair of parallel shafts 49 and 50 which are mounted in stationary bearings 51 on the frame 10, on which they are adapted to be vertically reciprocated as hereinafter described. By reference to Fig. 2, it will be seen that both ends of the shaft 49 have fixed bearings 51, and that only the upper end of the shaft 50 has a fixed bearing 51. The lower end of the shaft 50 is screw-threaded into a movable cross-head 52. The cross-head is mounted in a guide 53 in which it is adapted to be vertically reciprocated by a connecting rod 54 whose lower end is connected to a crank pin 55 affixed to the forward end of a driving shaft 56. By means of the crank pin 55 and the connecting rod 54, the cross-head 52 is adapted to be reciprocated within a definite range of movement, and the head 45 is 90 adapted to be adjusted relatively to the cross-head 52 by means of the screw-threaded connection between the shaft 50 and the cross-head. For this purpose, the shaft 50 is provided with a fixed hand wheel 57, by 95 which it may be turned, and a lock nut 58 by which it may be prevented from turning. The hand wheel 57 is set in the head 45 in such a way that, while it may be turned relatively thereto to adjust the shaft 50, it 100 cannot move vertically without moving the head 45 with it.

The forward end of the driving shaft 56 has its bearing in a rigid cross-piece 57 of the frame, while the rear end thereof has 105 its bearing in a sleeve 58 which is adapted to rotate relatively thereto. The rear end of the sleeve 58 is provided with a driving pulley 59 and the forward end thereof is provided with a fly-wheel 60, both of which 110 are keyed to the sleeve. That portion of the sleeve 58 intervening between pulley 59 and fly-wheel 60 is mounted and adapted to rotate in a bearing 61 on the frame 10. By means of so constructing and mounting the 115 members 58, 59 and 60, they are adapted to be driven and rotated as a unit without affecting the shaft 56. The forward end of the sleeve 58 is provided with clutch teeth 62 which are adapted to be engaged by and to rotate a collar 63 splined upon the shaft 56, and having complementary clutch teeth 64. The collar 63 is normally held by a spring 65 so that its teeth are in operative engagement with the teeth on the sleeve 58, thus 120 establishing a driving connection between the pulley 59 and the shaft. The collar is also provided with a circumferential groove 66 of which the greater part is in a plane at right angles to the shaft, and of which one 125 130

end is inclined to that plane so as to form a cam face 67. The groove 66 is adapted to receive an antifriction roll 68 mounted upon one end of a rod or controller 69. The controller 69 is mounted in a fixed bearing on the frame and is provided with a spring 70 which normally tends to force the roll 68 into the groove 66, and consequently into the path of rotation of a shoulder 71 at the inclined end of the groove 66. Thus when the roll 68 occupies the groove 66, it not only holds the teeth 64 away from the teeth 62, but it holds the collar and consequently the shaft 56 against rotation. When it is desired to let the movable clutch member into operative engagement with the relatively stationary clutch member so as to establish driving connection between the pulley 59 and the driving shaft, the controller 69 is retracted against the tension of the spring 70 by the means hereinafter described.

As hereinbefore stated, the rock shaft 29 is provided with an arm 32, by which it is held in normal position through the agency of the spring 33. The free end of this arm 32 is adapted to engage and move a dog 72 which is pivotally connected by a pin 73 to a yoke 74 affixed to the outer end of the controller. The under face of the dog 72 is adapted to rest by gravity upon a stationary mounted antifriction roll 75, by which the dog is supported when in its normal position so that its free end lies in the path of movement of the free end of the arm 32.

The operation of the machine is as follows, assuming that the clutch members are disengaged, and that the jack 11 is in its depressed or retracted position. The shoe is first placed upon the heel rest 35, as shown in Fig. 7, and the jack 11 tilted on its pivot 14 so that it stands in alinement with the upright shaft 13 and the knife 12. When the jack is in this position, the treadle 31 is elevated and the arm 32 is in the position indicated by dotted lines in Fig. 3. The first step on the part of the operator is to depress the treadle so as to rock the shaft 29 and cause the latter through its several connections, to rotate the cam member 17 and so raise the jack to operative position. When so rotated, the member 17 takes the position shown in Fig. 6, and the arm 32 takes the position shown by full lines in Fig. 3. By comparison of these two figures, it will be seen that the squared end 26 of the cam 17 moves into engagement with the squared end 25 of the member 16, thus relieving the rock shaft of the weight and pressure of the jack before the arm 32 engages the free end of the dog 72. This operation of moving the jack into operative position may occupy approximately one-half of the downward movement of the treadle. Subsequent downward movement of the treadle causes the arm 32 to move

farther to the right as in Fig. 3, thereby moving the dog 72, the yoke 74 and the controller 69 also to the right. The roll 68 is thus withdrawn from the groove 66 in the collar 63 and the spring 65 then projects the collar so that the teeth 64 operatively engage the teeth 62 and establish driving connection between the sleeve 58 and the shaft 56. When the collar 63 is thus thrown into engagement with the sleeve 58, the entrance to the groove 66 is brought into alinement with the roll 68, and the collar then rotates with the sleeve. The under face of the dog 72 is provided with an inclined face 76 which causes the free end of the dog to rise as it advances relatively to the roll. When the dog 72 has advanced so far as to cause the complete withdrawal of the roll 68 from the groove 66, the free end of the dog 72 is so far raised by reason of its inclined face 76 that it becomes disengaged from the free end of the arm 32 and is subsequently projected back to its former position by the spring 70. By the time this latter movement of the dog takes place, the collar 63 has been partially rotated by the clutch in the direction of the arrow in Fig. 3, thereby carrying the entrance to the groove 66 into a position where it registers with the roll 68. As the collar 63 continues to rotate, the roll enters into the groove 66 by reason of the action of the spring 70. When the inclined portion 67 of the groove 66 moves into engagement with the roll 68, the collar 63 is thereby moved again away from the sleeve 58 so that the teeth 64 and 62 become disengaged (see Fig. 5) and the shoulder 71 at the end of the groove 66 once more engages the roll 68 by which its rotation is arrested. The collar 63 has thus been permitted to make one complete revolution thereby imparting to the head 45 and the cutting knife 12, a downward and an upward stroke.

During the last described operation, the treadle 31 is held in its depressed position in which the free end of the arm 32 and the dog 72 occupy the position shown by Fig. 8. This completes the cutting operation and the shoe is then ready to be removed from the jack. When the operator releases the treadle 31, it is elevated by reason of the tension exerted by the spring 33 upon the arm 32, and the rock shaft 29 is therefore rocked so as to cause the cam member 17 to return to its initial position as shown in Figs. 1 and 2. The jack is therefore permitted to gravitate to its retracted position so that it may be swung about its pivot 14 sufficiently to permit the removal of the shoe.

In adjusting the knife 12, it is important to so position it with relation to the head 45 that, when the head is reciprocated to

- its lowest position, the cutting edge of the knife shall descend precisely to the transverse plane of the under surface of the fixed stop or work gage 37. It will be apparent 5 therefore that when the knife is so adjusted and the upper surface of the shank *b* is held in engagement with the under surface of the work gage 37, that the knife in its downward stroke will descend precisely to 10 and yet not into the shank. The cutting edge of the knife is preferably curved so as to conform to the curvature of the shank, in which case, the arch of the cutting edge is adjusted to cut to the plane of the work 15 gage. When the work rest, work gage, and the cutting knife are so constructed and arranged and operated with relation to each other, it is clear that the cutting knife must in every case, cut completely down to the 20 shank of the shoe, and that it cannot in any case cut beyond the surface of the shank irrespective of whatever may be the thickness of the heel or of the shank. So in trimming the breast of the heels of a great number of shoes, there is no necessity for varying the adjustment of these coöperating parts to compensate for varying thicknesses 25 of the work.
- Having thus explained the nature of my 30 said invention and described a way of constructing and using the same, although without attempting to set forth all of the forms in which it may be made, or all of the modes of its use, I declare that what 35 I claim is:—
1. A heel-breasting machine comprising a main frame, a movable jack for the shoe to be breasted, a rest plate for engagement with the face of the heel, spring-tensioned means connecting said rest plate to the 40 main frame, an unyielding reciprocatory knife and knife carrier having a path of unvarying length, and a stop attached to the main frame to engage the shank of the shoe and to resist unyielding pressure of the shoe moved thereagainst by the jack so as to position it with respect to the limit of the cutting movement of the knife, power-transmitting mechanism for positively reciprocating said knife carrier, and mechanism for moving said jack to engage the shank of the shoe with said stop and the heel of the shoe with said yielding rest plate.
  2. A power-driven heel-breasting machine, comprising a main frame, a reciprocatory jack, a knife moved in an unvarying path to breast the heel, a power shaft and power-transmitting mechanism to reciprocate said knife, a fixed shank-engaging stop to position the shoe with respect to the knife, and a spring-tensioned member mounted upon the frame independently of the knife and the jack yieldingly to engage the face of the heel and press the heel 55 against the jack.

In testimony whereof I have affixed my signature, in presence of two witnesses.

EDWARD ERICKSON.
